BLACKBOARD

Howard E. Steele, Los Angeles, Calif.

Application November 15, 1948, Serial No. 149,633

Term of patent 14 years

(Cl. D25—1)

To all whom it may concern:

Be it known that I, Howard E. Steele, a citizen of the United States, residing in Los Angeles, in the county of Los Angeles and State of California, have invented a new, original, and ornamental Design for a Blackboard, of which the following is a specification, reference being had to the accompanying drawing forming a part thereof:

Figure 1 is a front elevational view of a blackboard showing my new design.

Figure 2 is a view in side elevation of the blackboard shown in Figure 1.

The drawing has been shaded for color.

I claim:

The ornamental design for a blackboard as shown and described.

HOWARD E. STEELE.
